ROTARY BUFF

Morris Schloss, Bronx, N. Y.

Application July 20, 1951, Serial No. 237,750

14 Claims. (Cl. 51—193)

1

The present invention pertains to improvements in rotary buffs, being a continuation in part of my copending application Serial Number 776,302, dated September 26, 1947, which matured into Patent Number 2,576,364 on November 27, 1951.

An object of the invention is to provide an annular buffing section of improved firmness and strength, formed of bias-cut fabric including principal working or warp threads characterized by greater stiffness, hardness or toughness than the accompanying soft filler or woof threads, and in which all the said working or warp threads in the working zone of the buff are inclined from the radial in the same rotational direction.

A further object is to provide a buffing section of the above type particularly adaptable to heavy loads and high speeds.

A further object is to provide such a buffing section having a plurality of helically related internal plies preferably formed of a continuous strip of the above-noted type of bias-cut fabric, but including an individual outer guard ply of continuous construction on each side of the helically constructed portion, by which means flapping or catching of either end of the helical strip is prevented, regardless of the direction of rotation.

Another object is to provide an annular buffing section of the above type in which the fabric is formed in a series of uniform convolutions packed and clamped at the inner zone of the annulus and tapering outward to shallow waves at the outer circumference, each convolution comprising all plies of the section whereby the plies are mutually supporting in firm relation.

A still further object is to provide improved holding and reinforcing means for the inner zone of the convolutions, preferably including a combination of clamping pressure, and metallic stapling.

Another object is to provide a buffing section of the above type in which the contour and firmness of the radially tapering convolutions are adapted to provide a centrifugal fanning action.

Still another object is to provide such a buffer section including an improved hub plate having fan means to supply cooling air to the interior of the section equally effectively in either direction of rotation of the buff.

Other objects and advantages of the invention will become evident during the course of the following description in connection with the accompanying drawings, in which:

Figure 1 is a cross sectional view of a preferred form of the improved buffing section;

Figure 2 is a reduced edgewise view of the same;

Figure 3 is an axial elevation of the same in the direction 3—3, Figure 2;

Figure 4 is a similar axial elevation in the direction 4—4, Figure 2;

2

Figure 5 is a fragmental sectional view of a pair of fan tabs;

Figure 6 illustrates a plurality of the sections secured on a suitable rotary shaft;

Figure 7 is an enlarged fragmental view illustrating the operation of rearwardly inclined peripheral working or warp threads in the rotary buffing section;

Figure 8 is a similar view illustrating the operation with the peripheral working threads inclined forwardly;

Figure 9 illustrates a web of fabric of suitable type for making the improved buff;

Figure 10 illustrates the bias cutting of the web into sections;

Figure 11 shows a plurality of the bias-cut sections served end-to-end to form a continuous strip of any desired length, illustrating the unidirectional slant of all the warp or working threads;

Figure 12 shows a preferred first step in forming a buffing section, by rolling the bias-cut strip into a hollow cylinder;

Figure 13 is a line diagram illustrating the outer and inner plies of the cylinder cut for forming the guard plies;

Figure 14 is a similar diagram showing the ends of the guard plies joined to form continuous cylindrical plies;

Figure 15 is a diagram illustrating the tendency for the leading corner of an unguarded spiral buff to catch or flap as objects engage it, and

Figure 16 is a similar diagram illustrating how such catching or flapping is prevented by the guard plies of the present invention.

Referring to Figures 1, 2, 3, and 4, the numeral 20 generally denotes an annular rotary buffing section comprising a plurality of layers of bias-cut fabric having relatively stiff warp threads supported by soft woof threads, the inner plies 21 being preferably formed from a single strip disposed in generally helical relation, while the outer two plies 22 and 23, hereinafter termed guard plies, are individual plies of continuous construction. All plies are drawn together in a series of uniform convolutions 24, Figure 1, forming the inner circumference of the annulus.

The convolutions 24 are tightly pressed and held together in the following manner: A hub plate 26, preferably of metal, is placed on one side of the annulus and a binder ring 27 is placed on the opposite side. The ring and plate are pressed toward each other, compressing the convolutions tightly, and a row of metallic staples 28 is driven through the assembly and clinched, thus binding the parts permanently together. The staples 28 of the row are preferably slanted as shown in Figure 3, in order to insure even double stapling through all convolutions 24 and provide in the inner zone of the buff a reinforced unitary structure of great strength. The diagonal arrangement of the staples 28 accomplishes

the above result while allowing staples of adjacent buffing sections to nest together after the manner of a dog clutch, preventing tendency to rotary slippage and surface riding of staples between such adjacent sections. Due to the construction described, the buff may be operated successfully at speeds much higher than those at which prior buffs tend to fly apart under centrifugal force. However, the shape of the convolutions 24 provides small interstices 25 through which ventilating air may pass as hereinafter noted.

The hub plate 26 is provided with a central hole 29, Figures 1, 3 and 4, adapted to fit a rotary shaft 30 as shown in Figure 6. The inner edge of the plate is extruded axially and rolled outward at 31 to embrace frictionally the inner edge of an auxiliary plate or shutter 32. The shutter is formed with a plurality of pairs of oppositely inclined tabs or fan blades 33 and 33a, while the hub plate 26 is provided with a series of spaced openings 34. The plate 32 is held in the rolled joint 31 with sufficient friction to prevent accidental turning, but may be rotatively adjusted to bring the blades 33 and 33a into any desired registry with the openings 34. Referring to detail Figure 5, the auxiliary plate or shutter 32 may be set as shown in full lines when the rotation is that indicated by the full arrow, the blades 33 being adapted to drive air through the openings 34. For rotation in the opposite direction the plate 32 is set as shown in dot-and-dash lines the blades 33a being operatively registered with the openings 34 to scoop the air therethrough. The amount of air blown may be varied as desired by adjusting the plate or shutter 32 to close off various portions of the openings 34, up to and including complete closure if no circulation should be required in certain cases.

It will be evident the combination described not only provides wide adjustability, but also provides equally efficient forced draft through the plate 26 in either direction of rotation. The reason for and advantage of this provision will be hereinafter set forth in detail.

It has been noted that in the present invention all the principal peripheral threads; that is, the comparatively stiff grain, warp or working threads of the buffing section are inclined from the radial in the same relative rotational direction. By this means a dual-purpose buffing section is produced which is adapted to roughing at highest efficiency when revolved in one direction relative to the slant of the warp threads and to polishing at equally high efficiency when turned about so as to revolve in the other direction relative to the slant of the warp threads. The means by which this result is accomplished is as follows:

Referring to Figure 9, the numeral 35 generally denotes a portion of a web of fabric suitable for use in the invention, the essential qualification being that the longitudinal or warp threads 36 have a comparatively high degree of stiffness as contrasted with the softness of the transverse woof or filler threads 37. This comparative stiffness of the warp threads may be produced in various ways, such as the use of heavier or harder-twisted threads in the warp, by using sized threads in the warp while leaving the woof unsized, or if desired by using different materials in the warp and woof.

To prepare the fabric for use in forming the improved buffing section, the web 35 is cut into bias or diagonal strips 38 as shown in Figure 10,

10 after which a plurality of the strips 38 are joined end to end as at 39, Figure 11, to form a continuous bias strip 40 of length dependent on the diameter and required number of plies in the buff. It will be seen that in such a strip 40 all the stiff warp or working threads 36 lie parallel in the same diagonal direction across the single-ply strip, while the soft filler threads 37 lie parallel to each other in the opposite diagonal direction.

The single-ply bias strip 40, without pre-folding or gathering, may be rolled tightly into a hollow cylinder 41, Figure 12, in which the working threads 36 throughout all the spiral plies obviously maintain parallel helical relationship.

To form the final annulus as shown in Figure 1, one end of the cylinder 41 is contracted in a series of uniform convolutions by any suitable method, for example that shown and described 20 in the above noted copending application Serial Number 776,302, now Patent No. 2,576,364. It will be noted that each convolution 24 comprises all the plies of the section, and due to the lack of any gathering, ruffling or folding of the individual plies, all the latter fit closely together. The convolutions 24 taper outward to become 25 shallow waves 42 at the periphery, as shown in Figure 2, so that the buffing section comprises a series of evenly spaced radial corrugations 30 in which the closely fitting plies are mutually supporting throughout. The result of this construction is an annulus having a degree of 35 rigidity and balance not attainable in buffs involving gathering or folding of the individual plies, in which latter type of structures the necessarily haphazard mutual relationship of the plies prevents them from closely fitting and supporting each other.

Since, as previously noted, the relatively stiff 40 warp threads 36 in the cylinder 41 are all inclined in the same bias direction, and since the annulus is formed by contraction of one end of the cylinder rather than the middle thereof, all the threads 36 in the working zone of the completed section 29 are inclined from the radial 45 in the same rotational direction, as illustrated in Figures 3 and 4.

Due to the structure of the fabric described, substantially all of the work of buffing is performed by the stiff warp threads 36, the soft woof threads 37 merely serving to support the warp threads, give weaving body to the fabric, and to retain buffing compounds. The warp threads 36 may therefore be termed the working threads, and since they all incline from the radial in the 55 same circular direction as noted, it will be evident that the nature of the work done when the working threads engage the work in one angular direction will be different from that produced when the angular direction of contact is reversed. These differing effects are illustrated in Figure 7 and Figure 8.

Referring to Figure 7, the buff 20 is shown revolving in such a direction that the working threads 36 engage a work piece 54 with a rearward slant. In this case the threads yield rearwardly as shown, gliding readily over the surface of the work in a manner adapted ideally to polishing. When the relative direction of contact is that shown in Figure 8, the forward inclination of the relatively stiff working or warp threads 36 causes them to strike the work piece 54 substantially endwise, so that they tend to dig into the work surface and remove comparatively large amounts of material therefrom. With this

mode of operation, therefore, the buff is particularly adapted to roughing or cutting.

From the foregoing it will be seen that the present invention comprises a dual purpose buff specifically adaptable to two differing types of work merely by choosing the direction of rotation with respect to the slant of the working or warp threads 36. Since in either roughing or polishing all the warp threads 36 share the work equally, durability and efficiency are maximum, and the previously described inherent firmness and strength of the annulus permit the application of high pressures and high speeds with attendant great improvement in work-rate. It will further be seen that the described structure and its optimum results could not be attained if the strip from which the buff is made were either gathered or folded prior to its forming into the annulus. In the case of gathered strips the firm uniform convolutions and mutually supporting relation of the plies are prevented as previously noted. Similarly in the case of either longitudinal or transverse pre-folding unidirectional slope of all the peripheral warp or working threads would be rendered impossible, since due to the geometry of bias cut fabric, warp threads on opposite side of such a fold are necessarily slanted in opposite angular directions. Consequently, in a folded buff half the peripheral warp threads would be slanted in one rotational direction and half in the other, resulting in a hybrid surface properly adapted neither to efficient roughing nor polishing, regardless of the direction of rotation. The superiority of the present dual-purpose invention over any such structure will be obvious.

Figures 13 to 16 illustrate diagrammatically the formation and operation of the outer guard plies 23 and 24. Prior to forming the fabric cylinder 41 into the annulus as previously set forth, longitudinal slits 43 and 44 are made in the layers of fabric just underlying the ends of the strip as shown in Figure 13. The inner layer is then sewed together at 45, Figure 14, and a similar seam 46 joins the outer layer. Thus the inner and outer layers become continuous cylinders. When the cylinder 41 is formed into the annulus 20 these layers become the continuous guard plies 23 and 24 on the outside of the helical layers 21, still retaining their unidirectional warp thread arrangement.

Figure 15 illustrates diagrammatically the tendency of an unguarded helical buff to develop flapping and catching at its leading edge. When such a buffing section, either operated alone or at one end of a multi-section assembly, is revolved in such a direction that an edge 47 of a ply 21 is exposed in a forward direction, this edge tends to be forced outward by air pressure and to catch on any work-piece 53 which may engage the corner or outer face of the buff. Such catching or flapping would be obviously undesirable from the standpoints both of proper operation and durability of the buff. In the present structure, however, the continuous outer layers 23 and 24 act both as windshields and guards against catching of the work 53, regardless of the direction of rotation, as illustrated in Figure 16.

The operation of the fan blades 33 and 33a in a multiple section buff is shown in Figure 6. Referring to this figure, the numeral 48 designates a rotary spindle on which are mounted a plurality of sections 20, held between end plates 49 and 50. Since the sections 20 are of the dual-pur-

pose type previously described, they are so placed on the spindle that the warp threads of all sections are inclined in one direction or the other relative to the direction of rotation, depending on whether roughing or polishing is desired. The central openings 29 of the hub plates 26 fit on the spindle 48, accurately centering all sections with the spindle and with each other.

The high working speeds and pressure for which the sections 20 are adapted give rise to considerable heat, and it is essential that such heat be efficiently removed. For this purpose the end plates 49 and 50 may be provided with openings 51 and 52. When the buff is revolved the fan blades 33 and 33a form a blast of air through the interior thereof, dissipating heat from the plates 26 and from the inner surfaces of the fabric convolutions 24. Due to the absence of any liner inside the convolutions, the latter are directly exposed to the moving air, with consequent maximum heat removal. The provision of blades 33 and 33a as noted in respect to Figure 6, insures an equally effective positive blast when the sections 20 are orientated either for polishing or roughing, a result which could not be achieved if only one set of blades were provided.

The fabric corrugations 24-42, due to their permanent shape and the inherent stability of their structure as previously set forth are adapted to act as efficient centrifugal fan blades to force air rapidly outward. Since as noted, no inner liner restricts the access of air to the inner convolution surfaces, this centrifugal action draws air outward through the interstices in the convolutions, providing additional effective cooling.

A further advantage in the firm corrugated annular structure lies in the fact that fewer sections are required per linear inch of buff surface than with conventional buffs. Not only does this effect a saving in cost, but the "open" nature of the buffing surface, as provided by the peripheral waves of adjacent sections, causes air to be carried directly against the surface being worked, with consequent additional direct heat removal.

While the invention has been set forth in preferred form, it is not limited to the exact structures illustrated as various modifications may be made without departing from the scope of the appended claims.

What is claimed is:

1. In a rotary annular buff, in combination, a plurality of individually ungathered helical plies of bias-cut fabric, said fabric comprising relatively stiff warp threads and relatively soft filler threads, a continuous guard ply of said fabric on each side of said plurality of helical plies, all said warp threads throughout the outer zone of said buff including said guard plies being inclined from the radial in the same rotational direction, and means to secure said plies directly together throughout the inner circumferential zone of said buff.

2. The combination claimed in claim 1 wherein said fabric plies are formed in a series of uniform convolutions in said inner zone, each of said convolutions comprising all said plies in direct closely pressed relation, whereby said plies may be mutually supporting throughout said buff.

3. The combination claimed in claim 1 wherein said fabric plies are formed in a series of uniform convolutions in said inner zone, each of said convolutions comprising all said plies in closely pressed relation, whereby said plies may be mutually supporting throughout said buff, and wherein said securing means includes a hub plate

engaging one side of said inner circumferential zone, a clamping ring engaging the other side of said zone, and a plurality of staples clinched in circumferentially over-lapping relationship through said hub plate and said fabric convolutions and said binding ring.

4. In a rotary annular buff, in combination, a plurality of individually ungathered plies of bias-cut fabric having relatively stiff warp threads and relatively soft filler threads, said plies being formed in a series of uniform convolutions each comprising all said plies in the inner circumferential zone of said buff, all said relatively stiff warp threads in the outer zone of said buff being inclined from the radial in the same relative rotational direction, and means to secure said convolutions together in said inner zone.

5. The combination claimed in claim 4 wherein the outermost of said plies on both sides of said buff are of continuous construction, whereby said plies are guarded against flapping and catching on work objects engaging the same.

6. In a rotary annular buff, in combination, a plurality of helical plies of bias-cut fabric having relatively stiff warp threads and relatively soft filler threads, said plies in the inner circumferential zone of said buff being individually ungathered but being collectively formed in a series of uniform convolutions each comprising all said plies, all said relatively stiff warp threads in the outer zone of said buff being inclined from the radial in the same relative rotational direction, and means to clamp said convolutions together in said inner zone.

7. In a rotary buff, in combination, an annulus including a plurality of helical plies of bias-cut fabric comprising relatively stiff working threads and relatively soft filler threads, a continuous guard ply of said fabric on each side of said plurality of helical plies, said plies being formed in a series of uniform convolutions each comprising all said plies in the inner circumferential zone of said annulus, all said working threads throughout the outer zone of said annulus being inclined from the radial in the same relative rotational direction, a hub plate engaging one side of said inner zone, a ring engaging the other side of said zone, means to clamp said plate and said fabric plies and said ring together while retaining the inner edges of said plies exposed, said hub plate having a plurality of circumferentially spaced openings therein, a shutter movably secured on one side of said plate, and a plurality of pairs of oppositely slanted fan blades on said shutter, said shutter being rotarily adjustable on said plate to bring said blades selectively into cooperative registry with said openings, whereby air may be driven through said openings by rotation of said buff in either relative direction.

8. The combination claimed in claim 7 wherein in said hub plate is of metal and has a circular central guide opening adapted to engage a shaft, said shutter having a circular central opening, and wherein the metal of said plate surrounding said guide opening is extended axially through said opening in said shutter and flared radially to engage frictionally the exposed face of said shutter.

9. In a rotary buffing section, in combination, a fabric annulus, a metallic hub plate secured to the inner zone of said annulus and having a central circular guide opening adapted to engage a shaft, an axial extension of said hub plate surrounding said opening, a shutter plate rotatably

mounted on said axial extension with one face against said hub plate within said annulus, a radial flange on the end of said extension and frictionally engaging the other face of said shutter plate, said hub plate having a plurality of circumferentially spaced apertures, and a plurality of pairs of oppositely inclined fan blades on said shutter plate and adapted to be selectively positioned in cooperative registry with said apertures by rotation of said shutter plate on said axial extension.

10. In a rotary buffing section, in combination, a fabric annulus, a hub plate secured to the inner zone of said annulus, said plate having a central guide opening adapted to engage a shaft and also having a plurality of circumferentially spaced air apertures, a shutter movably secured to said plate and adjustable thereon to control the opening extent of said apertures, and a plurality of pairs of oppositely slanted fan blades on said shutter adapted to be selectively positioned in cooperative relation with said apertures by said adjustment of said shutter.

11. In an annular rotary buff, in combination, a plurality of individually unruffled helical plies of bias-cut fabric comprising relatively stiff working threads and relatively soft filler threads, and a continuous guard ply of said fabric on each side of said plurality of helical plies, said plies being formed in a series of uniform convolutions in the inner zone of said buff and tapering to radial corrugations extending to the periphery of said buff, all said working threads in the outer zone of said buff being inclined from the radial in the same relative rotational direction, and each of said convolutions comprising all said layers in closely pressed relation, whereby said layers may be mutually supporting throughout said buff.

12. The combination claimed in claim 11 including a hub plate engaging one side of said inner fabric zone, an annular ring engaging the other side of said zone, and a plurality of staples clinched in circumferentially over-lapping relationship through said plate, fabric convolutions and ring to secure the same tightly together.

13. An annular buffing section comprising a plurality of plies of unruffled bias-cut fabric having relatively stiff warp threads and relatively soft filler threads, all said stiffer warp threads in the outer zone of said section being inclined from the radial in the same relative rotational direction.

14. An annular buffing section comprising a plurality of individually ungathered helical plies of bias-cut fabric having relatively stiff warp threads and relatively soft woof threads, all said warp threads in the outer zone of said section being inclined from the radial in the same relative rotational direction.
